INVENTOR.
WILLIS R. HORNBERGER

or
George W. Gaynell
ATTORNEY

UNITED STATES PATENT OFFICE.

WILLIS R. HORNBERGER, OF EAST CLEVELAND, OHIO.

HINGE.

Application filed August 2, 1922. Serial No. 579,104.

To all whom it may concern.

Be it known that I, WILLIS R. HORNBERGER, a citizen of the United States, resident of East Cleveland, county of Cuyahoga, and 5 State of Ohio, have invented new and useful Improvements in Hinges, of which the following is a specification, the principle of the invention being herein explained and the best mode in which I have contemplated applying that principle, so as to distinguish 10 it from other inventions.

My invention relates to hinges, and particularly to hinges adapted for use in the operation of such building fixtures as doors, 15 windows, etc. The objects of the invention are to design a hinge for such purposes which shall serve, first, to so dispose the movable member in its open position as to conserve considerable of the space taken up 20 by the movable member in its open position by the use of the forms of hinges at present in general use; a hinge which shall be easily assembled in working position; and which shall be very effective in use.

25 The annexed drawings and the following description set forth in detail certain means embodying my invention, such means disclosing, however, but one of the various forms in which the principle of the invention may be applied.

In said annexed drawings:

Figure 1 represents a front elevation, taken from the plane indicated by the line I—I, Figure 2, of the elements forming one of my 35 improved hinges, the same being adapted for use as a bottom door hinge, a cover plate being removed; and fragmentary portions of the floor, and door-jamb being shown in section, the door being in extreme closed 40 position. Figure 1^a represents a fragmentary vertical section, taken in the plane indicated by the line I^a—I^a, Figure 1. Figure 1^b represents a fragmentary vertical section, taken in the plane indicated by the line I^b—I^b, Figure 1.

Figure 2 represents a plan section, taken in the plane indicated by the line II—II, Figure 1, intermediate and extreme open positions of the door and hinge being also 50 shown by dot and dash lines;

Figure 3 represents a front elevation of an upper door hinge, with a cover plate removed, and adjacent co-operating door and door-jamb elements; Figure 3^a represents a 55 fragmentary vertical section, taken in the

plane indicated by the line III^a—III^a, Figure 3;

Figure 4 represents a plan section, taken in the plane indicated by the line IV—IV, Figure 3;

Figure 5 represents an elevation, upon a reduced scale, of complete double doors equipped with my improved hinges, the same being shown in closed position; and

Figure 6 represents a plan section, taken in the plane indicated by the line VI—VI, Figure 5, the doors being shown also in extreme open position by dot-and-dash lines.

Referring to the annexed drawings in which the several ordinals denote the same 70 parts in the several views, I indicate a door-jamb by the ordinal 1 and a section of a building floor by the ordinal 2. Within the opening 4 in the jamb 1 a door 10 is hung by my improved hinge. The door 10 is 75 mounted at the top in the jamb 1 and at the bottom on the floor 2. The connection between the door 10 and jamb 1 at the top and the door 10 and the floor 2 at the bottom consists in each instance of two links secured at each of their ends. I designate the lower links by the ordinals 11 and 12 and the upper links by the ordinals 13 and 14. I intend the opening of the movable member, such as a door or window, to be effected by 80 pressure suitably applied thereon, such as through the medium of a suitable hand member or knob 5, the pivotally mounted ends of the links of the two pairs being so positioned that the resultant of tendency of the 85 door to swing on the door pivots of the links due to the pressure upon the door is to move the link end of the door away from the opening 4 in a direction opposite to that in which the pressure is applied, resulting, due to the pre-determined length and 90 positioning of the links, in bringing one face of the door adjacent to, preferably, and parallel with the vertical surface of that side of the jamb to which the links are connected, as plainly shown in the dot-and-dash lines positions of Figure 6, with substantially one-half of the door in each 95 of the building compartments that communicate through the opening 4. The links 11, 12, 13 and 14 are so positioned that one of each pair will act as a stop at the 100 respective extreme positions of the door 10 due to the interference therewith of the other link as plainly shown in the three different 105

110

positions illustrated in Figure 2. Furthermore, of course, the dimensions and positioning of the links 11, 12, 13 and 14 are so calculated that the links lie respectively 5 above and below the top and bottom edge of the door and do not extend laterally therefrom, in the extreme open or closed positions of the same, except in the case of the link 13, which, at the jamb end, extends 10 slightly laterally from the door 10, but is covered by the jamb 1 and is accommodated by the clearance 7 between the jamb 1 and door 10.

The link 11 is formed at the door end 15 with an integral upwardly projecting journal member 11' and the link 12 is formed with an integral upwardly projecting journal member 15 at the door end and at the floor end with an integral downwardly projecting 20 journal member 12'. Correspondingly the link 13 is formed with a downwardly projecting integral journal member 13' and the link 14 is formed with a downwardly projecting integral journal member 16 and 25 an upwardly projecting integral journal member 20. The journal members 11', 15, 13' and 16 are intended for incorporation within suitable door casings hereinafter fully described and the journal 17 and the adjacent corresponding end of the link 11 are 30 intended to be mounted in the floor 2; whereas, the journal 20 and the corresponding adjacent end of the link 13 are intended to be mounted in the upper section of the door jamb 1. Recesses 21 and 22 respectively are 35 chiseled out of the bottom and top edges of the door 1. Within these recesses are incorporated rectangular casings comprised of lateral angles 25 and 26 secured to the door 1 by means of the screws 27, inner plates 28 secured at their ends by means of screws 29 to the angles 25 and 26, and outer plates 30 secured to the door 10 by any suitable means, or, as shown, an integral part of the sheet 40 steel from which angles 25 and 26 are formed. Front covers for these rectangular casings are afforded by brass or bronze plates 45 secured to the door 10 by screws 23'.

A plate 31 is secured in the floor 2 by means 50 of screws 32, the same having a depending bushing member 18 seated in a suitable hole 3 formed in the floor 2 and receiving the depending journal member 17 of the link 12. Also, integrally formed with the plate 31, or 55 secured thereto with a driving fit, is an upwardly projecting journal member 19 accommodated by a suitable hole formed in the floor end of the link 11. Said link 11 is held to the journal 19 by means of a cover 60 plate 37 and a screw 38. The journal 17 is held to the bushing 18 by means of a bottom plate 33 and a screw 34. The top surface of floor plate 31 and the adjacent bottom surface of link 12 are formed with grooves, 65 Figure 1^b, which provide races for balls

36 positioned intermediate said members 12 and 31. Similarly, an upper plate 39 secured by screws 39' to the jamb 1 is provided with an upwardly extending bushing member 42 seated within a suitable recess 6 70 formed in the jamb 1 and receives the journal member 20 formed integral with the link 14. The adjacent jamb end of the link 13 is secured similarly to the floor end of the link 11 and the jamb ends of links 13 and 14 are held to position, similarly to the floor ends of links 11 and 12, by means of plates 33 and 37 and screws 34 and 38. The distance between the respective floor and jamb 75 pivotal axes is greater than between the respective door pivotal axes. 80

It will be noted from the accompanying drawings that the door ends of the links 11, 13 and 14 are pivotally secured to the outside plates 30 of the upper and lower rectangular door casings; whereas, the door end of the link 12 is provided with the journal member 15 of extended length so that the same intersects the inner casing 28. The purpose for which the journal member 15 is thus lengthened will be hereinafter fully explained. The detail for securing the door ends of the links 11, 12, 13 and 14 is plainly shown in Figure 3^a and consists of an externally threaded bushing 40 receiving the journal member 11', 15, 13' or 16, as the case may be, and a co-operating threaded opening 44 formed in the plate 30. The journal members 11', 13' and 16 are further provided with threaded portions 53 adapted to receive co-operating nuts 54 spaced from the bushing 40 by washers 55, also plainly shown in said Figure 3^a. The rectangular casings positioned in the recesses 21 and 22 may be unitary castings having the bushings 40 cast integral therewith. 100

The purpose of extending the journal member 15 is to afford means for securing one end of a spring 51 which shall tend to maintain the door 10 in extreme open or closed position. To this end I secure a tubular thrust member 45, Figure 1^a, upon the extension of the journal member 15 by means of key 52, said tubular member 45 having end flanges 47 and a cylindrical pin 46 secured to or formed integrally with said flanges and receiving the concave end surface 48' of a plate 48 having a flange 49. The other end of the plate 48 is tubular and receives one end of a pin 50 which is loosely mounted at its other end in the angle member 26, reciprocates in a slot 56 formed in the door 10, and is surrounded by the compression spring 51 bearing at one end against the flange 49 and at the other end against said angle member 26. The pin 50 and the member 48 may be made of one piece. The tendency of said spring 51 is to turn the tubular member 45, and hence the journal member 15 secured to the link 12, 115 120 125 130

into the position shown either in full lines in Figure 2 or in the left-hand dot-and-dash position, i. e., into either the closed or fully open position of the door 10, depending upon whether or not the said spring 51 is free to act upon the right side or left side of the intermediate position of the door 10 shown in the right-hand dot-and-dash position of Figure 2. According to the design of the elements this intermediate position of the door 10 illustrates the fully compressed condition of the spring 51 when the door is being moved positively from a closed or an open position to the opposite position.

15 What I claim is:

1. The combination with a flooring, a door jamb and a door; of a pair of links forming each of the top and bottom hinges; a jamb plate and a floor plate secured adjacent the ends of one vertical edge of the door, said jamb plate and said floor plate each being formed with two, and one end of each of the four links being formed with one, cooperating bearing surfaces and journal surfaces, and a pair of door plates secured respectively to the top and bottom edges of the door, said door plates and the other ends of the four links being formed with cooperating bearing and journal surfaces, the respective pairs of pivotal attachment points for the links being adjacent, the distance between the respective jamb and floor pivotal attachment points being greater than that between the respective door pivotal attachment points.

2. The combination with a flooring, a door jamb and a door; of a pair of links forming each of the top and bottom door hinges, a jamb plate and a floor plate secured adjacent the ends of one vertical edge of the door and each formed with a journal surface and a bearing surface, one end of each of the four links being formed with bearing and journal surfaces each cooperating with one of the aforementioned journal and bearing surfaces, and a pair of door plates secured respectively to the top and bottom edges of the door and formed each with a pair of bearing surfaces, the other ends of the four links being formed with cooperating journal surfaces, the respective pairs of pivotal attachment points for the links being adjacent, the distance between the respective jamb and floor pivotal attachment points being greater than that between the respective door pivotal attachment points.

3. The combination with a flooring, a door jamb and a door; of a pair of links forming each of the top and bottom hinges; a jamb plate and a floor plate secured adjacent the ends of one vertical edge of the door, said jamb plate and said floor plate each being formed with two, and one end of each of the four links being formed with one, cooperating bearing surfaces and journal surfaces, a

pair of door plates secured respectively to the top and bottom edges of the door, said door plates and the other ends of the four links being formed with cooperating bearing and journal surfaces, the respective pairs of pivotal attachment points for the links being adjacent, the distance between the respective jamb and floor pivotal attachment points being greater than that between the respective door pivotal attachment points, and means automatically tending positively to hold the door either in closed or extreme open position.

4. The combination with a flooring, a door jamb and a door; of a pair of links forming each of the top and bottom hinges; a jamb plate and a floor plate secured adjacent the ends of one vertical edge of the door, said jamb plate and said floor plate each being formed with two, and one end of each of the four links being formed with one, cooperating bearing surfaces and journal surfaces, and a pair of door plates secured respectively to the top and bottom edges of the door, said door plates and the other ends of the four links being formed with cooperating bearing and journal surfaces, the length of each link and the distance from its point of attachment to the door to the adjacent vertical door edge being each substantially one-quarter of the width of the door, the respective pairs of pivotal attachment points for the links being adjacent, the distance between the respective jamb and floor pivotal attachment points being greater than that between the respective door pivotal attachment points.

5. The combination with a flooring, a door jamb and a door; of a pair of links forming each of the top and bottom hinges; a jamb plate and a floor plate secured adjacent the ends of one vertical edge of the door, said jamb plate and said floor plate each being formed with two, and one end of each of the four links being formed with one, cooperating bearing surfaces and journal surfaces, and a pair of door plates secured respectively to the top and bottom edges of the door, said door plates and the other ends of the four links being formed with cooperating bearing and journal surfaces, the respective pairs of pivotal attachment points for the links being adjacent, the distance between the respective jamb and floor pivotal attachment points being greater than that between the respective door pivotal attachment points, one of the links at the closed and extreme open positions of the door acting as a stop to the movement of the other link in one direction.

6. The combination with a flooring, a door jamb and a door, said door having a pair of recesses formed respectively in the bottom and top edges thereof; of a pair of links forming each of the top and bottom

door hinges, a jamb plate and a floor plate secured adjacent the ends of one vertical edge of the door, said jamb plate and said floor plate being formed each with two, and one end of each of the four links being formed with one, cooperating bearing surfaces and journal surfaces, casings fitted to said door recesses and having cover plates, the outer wall of each casing and the other ends of the four links being formed with cooperating journal and bearing surfaces, the respective pairs of pivotal attachment points for the links being adjacent, the distance between the respective jamb and floor pivotal attachment points being greater than that between the respective door pivotal attachment points.

7. The combination with a flooring, a door jamb and a door, said door having a pair of recesses formed respectively in the bottom and top edges thereof; of a pair of links forming each of the top and bottom door hinges, a jamb plate and a floor plate secured adjacent the ends of one vertical edge of the door, said jamb plate and said floor plate being formed each with two, and one end of each of the four links being formed with one, cooperating bearing surfaces and journal surfaces, casings fitted to said door recesses and having cover plates, the outer wall of each casing and the other ends of the four links being formed with cooperating journal and bearing surfaces, the respective pairs of pivotal attachment points for the links being adjacent, the distance between the respective jamb and floor pivotal attachment points being greater than that between the respective door pivotal attachment points, one of the links at the

closed and extreme open positions of the 40 door acting as a stop to the movement of the other link in one direction.

8. The combination with a flooring, a door jamb and a door, said door having a pair of recesses formed respectively in the bottom and top edges thereof; of a pair of links forming each of the top and bottom door hinges, a jamb plate and a floor plate secured adjacent the ends of one vertical edge of the door and each formed with a journal surface and a bearing surface, one end of each of the four links being formed with a cooperating bearing surface or journal surface, casings fitted to said door recesses and having cover plates, a pair of inwardly extending bearings secured to the outer wall of each casing, the other ends of the four links being formed with cooperating journal surfaces, one of said journal surfaces being formed with an extension, a thrust member secured to said extension, a spring-actuated pin secured at one end to said thrust member, said door being further formed with a recess which allows for the reciprocation of said pin, the thrust member compressing the spring, as the door is opened and closed, for substantially one-half only of a complete door movement, whereby the spring tends positively completely to close and open the door, the respective pairs of pivotal attachment points for the links being adjacent, the distance between the respective jamb and floor pivotal attachment points being greater than that between the respective door pivotal attachment points.

Signed by me, this 31st day of July, 1922.

WILLIS R. HORNBERGER.
